UNDERGARMENT

Hallie Lee Jasper, Bridgeport, Conn., assignor to
 The La Resista Corset Company, Bridgeport,
 Conn., a corporation of Connecticut

Application July 31, 1939, Serial No. 287,609

2 Claims. (Cl. 2—73)

The present invention relates to improvements in undergarment, and particularly a lady's under-garment intended to combine in a single structure the functions of brassière, girdle and slip, or in a modified form of the invention to combine the functions of a girdle and skirt. It is an object to provide a garment which while being body conforming and molding will at the same time give complete freedom of movement in walking and sitting, and will provide an under-garment for use beneath light-weight dresses which will be entirely free in the front and back from transverse seams, ridges or overlaps. To this end it is proposed to provide front and back panels which extend in unbroken lines for the full vertical length of the garment. I am aware that garments have been proposed heretofore in which it was attempted to combine the functions of brassière, girdle and slip, but in these the skirt extension was simply secured to the lower end of a girdle section providing a seam and overlap either extending entirely about the garment or across either the front or rear panels. This not only resulted in discomfort and a failure to obtain a continuous unbroken front and rear profile, but in the use of such garments with sheer tight fitting outer dresses produced an unsightly ridge.

A further object is to provide an under-garment in which side panels are provided of horizontal stretch elastic material extending from the upper edge to a point below the widest point of hips, and which in cooperation with fastening means disposed along the central line of the back panel are adapted to cause the garment to conform to and mold the body, drawing in the upper brassière portion of the garment, fitting into the waistline and cupping in at the sides and rear below the hips. It is a further object to provide a garment in which garters are incorporated and positioned at such points that the strain thereon will not disturb the fit of the garment or impose uncomfortable strains upon the wearer. It is further proposed to provide in the front and rear panels reinforcing lining portions localized with respect to and adapted to overlie the central portion of the diaphragm and abdomen and the central portion of the lower back, so that there will be substantial support of the body at these points, and the garment will present a smooth appearance.

Another object is to provide a garment particularly for use with sheer summer dresses or evening dresses, which while being relatively thin, light weight, and body conforming will at

the same time provide a relatively opaque under skirt thereby making the combined under-garment and outer dress shadow proof. It is further proposed to provide a garment of simple construction free from overlapping lining portions, so that the same may be conveniently laundered and will dry rapidly.

With the above and other objects in view, an embodiment of the invention is shown in the accompanying drawing, and this embodiment will be hereinafter more fully described with reference thereto, and the invention will be finally pointed out in the claims.

In the drawing:

Fig. 1 is a front plan view of a garment, according to the invention, the same being shown flattened out.

Fig. 2 is a rear plan view, and showing the fastening means partially opened.

Fig. 3 is a perspective view from the front showing the garment as worn.

Fig. 4 is a perspective view from the rear showing the garment as worn.

Fig. 5 is a perspective view, from the rear of a modified form of the invention, the upper line of the garment being at the waistline.

Similar reference characters indicate corresponding parts throughout the several figures of the drawing.

Referring to the drawing the under-garment, according to the exemplary embodiment of the invention illustrated in Figs. 1 to 4 of the drawing, comprises a front portion consisting of suitably shaped brassière portions 10—10, and a front panel 11 formed of two half sections 35 stitched along the central vertical seam 12, the upper edge of the front panel being shaped to extend between the brassière portions 10—10, as at 13, and to extend along the outer side of the brassière portions, as at 14—14. The side edges 40 of the front panel are slightly curved in along the waist section and flare outwardly along the hip and skirt sections. Upon the inner side of the front panel and in proximity to the diaphragm and abdomen engaging portions there is 45 provided a lining member 15 of vertically elongated diamond shape, secured by stitching 16. Between the upper point of this lining member and the brassière sections there is provided upon the outer surface a decorative panel 17 secured 50 by stitching 18, and which is preferably formed of the same material as the brassière sections. The two half-sections of the front panel each consist of vertically continuous and unitary upper and skirt portions, so that they form a con-

tinuous smooth contour, unbroken by transverse seams or different material textures in the upper and skirt portions.

The side sections of the garment comprise upper side portions 18-19 formed of horizontally stretchable elastic fabric which are secured to the outer edges of the front panel by rows of stitching 20-20, and extend from the upper edge of the side portion 14-14 to a point below the widest point of the hip line, the lower edges of the elastic side portions being cut diagonally downward from the side edges of the front panel, so that at the rear portion of the garment the elastic side portions extend in snug confining relation below the rear hip portions. To the lower inclined edges of the elastic side portions 19 there are respectively secured side skirt portions 21 formed of the same material as the front panel and cut to flare outwardly, the upper edges of these side skirt portions being secured by stitching 22 to form transverse seams and the forward side edges being secured by continuation of the stitching 20.

The rearward edges of the elastic side portions 25 are shaped so that at the upper portion they will form outwardly curved convex lines, at the waist portion will form inwardly curved concave lines, and below the waist portion they will form outwardly curved concave lines, the rearward edges 30 of the side skirt portions 21 being formed in a continuous line with the lower extremities of the elastic side portions 19.

The back panel 23 of the garment is formed in substantially similar manner to the front panel 25 of two half-sections secured by a central vertical seam 24 and these sections extend continuously in unbroken lines from the upper edge of the back to the lower edge of the garment, being secured at their outer edges to the elastic side portions 19 and the skirt portions 21 by continuous lines of stitching 25-25. In the assembled relation of the parts the ends of the transverse seams 22 of each side section are transversely opposite to vertically unbroken seamless portions 40 of the front and back panel sections. An opening 45 is provided along the central seam extending from the upper edge to a point contiguous to the waistline and is provided with pairs of hooks and eyes 26 and 27 secured upon tape portions 28 and 29 stitched to the underside of the back portion, and with a zipper fastener, the respective sides 30 and 31 of which are secured to the two edges of the opening and adapted to be secured by a slide member 32.

Upon the inner side of the back portion and at a point extending from the zipper fastened opening to a point below the hip line there is provided a lining panel 33 of vertically elongated diamond-shape secured by stitching 34. The back panel is provided with fullness in the region of the waist which allows the garment to conform

to the body under tension of the elastic side portions, and the lower portion is also provided with fullness to allow for the flare of the skirt.

Upon the inner surface of the front panel 11 and the side portions 19 there are secured garters 35, a pair at the front and two pairs at the rear. Shoulder straps 36-36 are secured between the brassière sections and the pack panel. The garment illustrated is for use with short dresses, that is, knee length or slightly below knee length, 10 but it will be understood that the skirt portion may be of any suitable length, and in the case of an evening gown for instance may be substantially floor length.

In Fig. 5 I have illustrated a modification in 15 which the invention combines the functions of a girdle and skirt. In this case the upper line of the garment is at the waistline, the arrangement of the front panel, the elastic side portions, the side skirt portions, and the rear panel being otherwise substantially similar to these portions in 20 the first embodiment. The parts are therefore given the same reference characters as the corresponding parts of the first embodiment.

I have illustrated and described a preferred 25 and satisfactory embodiment of the invention, but it will be obvious that changes may be made therein within the spirit and scope thereof, as defined in the appended claims.

Having thus described my invention, what I 30 claim and desire to secure by Letters Patent is:

1. A skirted foundation under-garment, comprising a pair of side sections, each consisting of an upper horizontally stretchable elastic portion extending from the upper edge of the garment to 35 a point below the widest point of the hip line and a lower non-elastic side skirt portion secured by a transverse seam to the lower edge of said elastic portion, the forward and rearward side edges of the upper elastic portions of said side sections 40 being vertically continuous with the forward and rearward side edges of the lower skirt portions, and front and back non-elastic panel sections having vertically continuous side edges substantially co-extensive with and secured to the respective forward and rearward side edges of said side sections, said transverse seam of each of said side sections having its ends transversely opposite to vertically unbroken seamless portions of said front and back panel sections, the part of said 50 garment in lateral line with said elastic side portions being body-conforming and the part below said elastic side portions constituting a non-body-conforming skirt portion.

2. The invention as defined in claim 1, further 55 characterized in that said transverse seam at each side being diagonally disposed and inclined downwardly from front to back.
